CATHODE RAY TUBE TERMINAL DEVICE OR SIMILAR ARTICLE

John B. Coppola, Stamford, Richard H. Podoloff,
Bethany, and Frederick E. Wahlenmeier, Nor-
walk, Conn., assignors to the Bunker-Ramo Cor-
poration, Stamford, Conn., a corporation of
Delaware

Filed Aug. 23, 1968, Ser. No. 13,243

Term of patent 14 years

Int. Cl. D14—02; D18—01

U.S. Cl. D26—5

The figure is a front, left side and top perspective view of a cathode ray tube terminal device or similar article showing our design.

The right side of the cathode ray tube terminal device of the figure is a mirror image of the side which is shown, while the back is conventional in appearance.

We claim:

The ornamental design for a cathode ray tube terminal device or similar article, as shown and described.
